SPOON OR SIMILAR ARTICLE

Kae E. Jones, New York, N.Y., assignor to Welling Ware, Inc., New York, N.Y., a corporation of New York

Application August 12, 1957, Serial No. 47,343

Term of patent 7 years

(Cl. D54—12)

Fig. 1 is a top plan view of a spoon or similar article, showing my new design.

Fig. 2 is a side view thereof.

Fig. 3 is a bottom plan view thereof.

Fig. 4 is a cross-sectional view taken on line 4—4 of Fig. 1, and drawn to an enlarged scale.

Fig. 5 is a cross-sectional view taken on line 5—5 of Fig. 1, and drawn to an enlarged scale.

Fig. 6 is an enlarged fragmentary view of part of the spoon of Fig. 1.

The essential features of my design reside in the configuration of the handle in combination with the particular type of ornamentation as applied thereto.

I claim:

The ornamental design for a spoon or similar article, substantially as shown and described.
